UNITED STATES PATENT OFFICE.

SAMUEL J. CLARK, OF DETROIT, MICHIGAN.

VINEGAR-GENERATOR.

SPECIFICATION forming part of Letters Patent No. 235,996, dated December 28, 1880.

Application filed January 13, 1879.

To all whom it may concern:

Be it known that I, SAMUEL J. CLARK, of Detroit, in the county of Wayne and State of Michigan, have invented an Improvement in 5 Vinegar-Generators, of which the following is a specification.

The nature of my invention relates to certain new and useful improvements in the construction of that class of devices employed in 10 converting cider into vinegar after the vinous fermentation (by which the lees of the cider is thrown off) has taken place.

The invention consists in the details of construction and the combination of said details, 15 as more fully hereinafter described.

Figure 1 is a perspective of a section of my improved generator, all the sections of which are alike, and connected together in a similar manner. Fig. 2 is a vertical longitudinal 20 central section.

In the accompanying drawings, which form a part of this specification, A represents a box, tight at each end, supported at the top of a suitable frame, one end of said box being slightly 25 elevated and provided with an opening, a, on its upper surface and near its highest point of elevation. In the bottom of the box there are driven series of wooden pegs b, projecting upward but a portion of the depth of the box. At the 30 lower end of the box there are perforations, into which are driven from below the hollow and perforated plugs c. These plugs are inclosed in a box, B, which forms a connection between the box A and a similar box, A', immediately 35 below. This box A' is inclined in the opposite direction from the one above, and is constructed in precisely a similar manner, except that the opening a' in its top is enlarged to the area of the box B. The opposite end of this box 40 A' is provided with similar perforations and similar perforated hollow plugs, the latter opening into a box, B', in the manner heretofore described. Thus I construct and build up, one above the other, as many of these boxes 45 as I may desire, each inclining in the opposite direction from the one above, and connected together by the boxes inclosing the hollow plugs. The bottom box, A², of the series is constructed like the others, except that it has 50 a perforation, d, for the discharge of the vinegar. The frame-work which sustains this se-

ries of inclined boxes incloses at each end a vertical air-chamber, C, closed at the top and open at the bottom. Perforations e in the inner walls of these chambers admit air into the 55 boxes B B', and steam-pipes D pass laterally through the lower ends of these chambers, said pipes communicating with any convenient steam-generator. Perforated diaphragms f are inserted in the lower ends of these chambers, to prevent the ingress of vinegar-flies or other insects.

In practice, these generators, when in use, should be set up in rooms that can be conveniently kept at a proper temperature to facilitate 65 fermentation. The cider to be used after the vinous fermentation has taken place is allowed to run in a small stream through the opening a in the upper box. In its passage down the incline the current is spread into a 70 thin film by means of the obstructing-pins, and is discharged from the lower end through the perforated plugs into the box below, through the connecting-box, and so on until the vinegar is withdrawn from the lower box. 75 The chambers at the ends of the generating-boxes are heated by the passage of steam through the steam-pipes, as described, and a portion of the heated air will pass through the 80 perforations in the inner walls of the chambers into the boxes, which afford communication between the horizontal box generators, while other portions of such air will pass upward, communicating heat to the ends of the 85 generator-boxes.

The various boxes necessary to form a perfect generator may be constructed with doors, as shown in the drawings, or other appliances by means of which access can be had to the interior when desired, and which, when closed, 90 will prevent the escape of the gases of fermentation.

The end which I accomplish is a very rapid generation of vinegar from cider, of uniform color and strength, by the flow of the cider in 95 thin films in inclosed boxes or generators under suitable conditions of heat.

I am aware that sloping troughs have heretofore been employed in vinegar-generating apparatus; and I am also aware that an apparatus for making vinegar consisting of a 100 box provided with a series of parallel horizon-

metal troughs provided with plates for retarding the passage of the liquid along them, the troughs communicating with each other by means of pipes, at one end of each trough, each of the said pipes being arranged on the side opposite to that on which the pipe on the trough above is arranged, the box being provided with holes in its sides and top for the passage of heated air introduced into the lower part of the box, has heretofore been employed, and I therefore lay no claim to such construction, my invention being confined to the details of construction set forth in the claim.

15 What I claim as my invention is—

The vinegar-generator described, consisting of the horizontal compartments A A' A'', inclined in opposite directions, and having pins b on their bottom boards, the vertical connecting-chambers B B', having perforated plugs 20 c, the vertical compartment C at the ends of the generator, the openings e, leading into the chambers B B', and the steam-pipes D, all constructed and arranged substantially as set forth and shown. 25

SAMUEL J. CLARK.
